UNITED STATES PATENT OFFICE.

ARTHUR E. CHAPPELL, OF CHICAGO, ILLINOIS.

SURFACING-ROLL.

1,191,399.

Specification of Letters Patent. Patented July 18, 1916.

Original application filed November 12, 1915, Serial No. 61,007. Divided and this application filed February 4, 1916. Serial No. 76,099.

To all whom it may concern:

Be it known that I, ARTHUR E. CHAPPELL, a citizen of the United States, residing at Chicago, in the county of Cook and State 5 of Illinois, have invented certain new and useful Improvements in Surfacing-Rolls, of which the following is a specification.

This invention relates in general to surfacing machines designed for producing 10 smooth surfaces on floors, bowling alleys and the like, and has more particular reference to the structure of the surfacing roll itself, this application being a division of my prior application, Serial No. 61,007, filed 15 November 12, 1915, for surfacing machine. Surfacing rolls of this general character are customarily of cylindrical form and are provided on their peripheries with a longitudinally extending and usually diagonally disposed slot through which the ends of the 20 sheet of abrading material, such as sand paper, emery paper or the like, are inserted. Clamping rollers arranged within the cylinder beneath and parallel with the slot are 25 adapted to clamp the inserted ends of the abrading sheet so that the sheet is securely held upon the periphery of the roll. Prior to my present invention these clamping rollers, so far as I am aware, have been journaled 30 in the ends of the cylinder in such a way that it was necessary, in order to remove the rollers for repairs or other purposes, to remove one end of the cylindrical surfacing roll. Since the ends of the surfacing roll 35 are rigidly and securely fastened to the central shaft and to the surrounding cylindrical walls the removal of an end necessitated the dismantling and disassembling of the roll structure and involved the expenditure 40 of considerable time and labor.

One of the primary objects of my present invention is to provide a surfacing roll in which the clamping rollers will be so mounted that they may be readily removed from 45 the interior of the roll without dismantling or disassembling the roll structure.

Another object of my invention is to provide a roll, the body of which will be of integral construction as distinguished from 50 built up structures comprising independent side and end walls such as have been previously employed.

Other objects and advantages of my invention will be readily appreciated as the

same becomes better understood by reference to the following description when considered in connection with the accompanying drawings.

Referring to the drawings Figure 1 is a plan view of a surfacing roll embodying my invention, certain portions being broken away to show the underlying parts; and Fig. 2 is an end elevation of the roll shown in Fig. 1.

On the drawings reference character 3 indicates the main shaft upon which the roll is mounted and by which it is rotated when in operation. The roll itself, so far as the mounting of the clamping rollers is concerned, may be of any preferred construction and material, but for purposes of economy and durability I have disclosed a roll comprising end walls 4 and 5 integrally united with the cylindrical peripheral walls 6, the walls being of cast metal construction 75 which provides a strong and durable roll at relatively low cost.

The sheet of abrading material 7 which may be of emery paper, sand paper or the like, is disposed around the periphery of 80 the cylinder in the usual manner, the ends of the sheet being inserted through the slot 8 extending from end to end of the roll in a diagonal direction. Beneath and parallel with the slot 8 are disposed the clamping 85 rollers 9 and 11, one or both of which has a flat face 12 which when opposed to the other roller provides a space through which the ends 13 of the abrading sheet may be inserted as shown in Fig. 2. One roller, in 90 this instance roller 11, has a squared shank projecting beyond the end wall of the roll to receive a wrench by which the roll may be rotated so as to firmly clamp and hold the ends of the abrading sheet in position, as 95 shown in Fig. 2. The left hand ends of the clamping rollers are journaled in suitable bearings 14 and 15 formed in the end wall 5, while the opposite ends are journaled in bearings formed in a plate 16 removably secured to the end wall 4 by screws or bolts 17.

In order to accommodate the plate or block 16 the end wall 4 is provided with a suitable opening 18 adapted to receive the block and the wall surrounding the opening is depressed as indicated at 19 to permit the peripheral flange 21 of the block to lie flush with the outer face of the wall 4.

It will be obvious that when it is desired to remove the clamping rollers for any purpose it is not necessary to dismantle or disassemble the entire roll, but by simply unfastening the screws 17 the plate or block 16 may be removed and the rollers may be withdrawn through the opening 18. In order to reassemble the rollers it is only necessary to insert them through the opening 18, 10 position them in the bearings 14 and 15 in the end wall 5 and then replace the plate or block 16 and secure it in position by the screws.

My improved manner of mounting the 15 clamping rollers provides a construction which can be economically manufactured and readily assembled, and while I prefer to employ a cast metal cylinder as a surfacing roll it should be manifest that this manner of mounting the clamping rollers can be 20 employed in connection with surfacing rolls of any preferred construction, such as built up metal structures or even wooden rolls if desired. My invention therefore is not limited 25 to the structural details shown and described but is capable of considerable modification and variation without departing from the scope thereof as defined in the following claims.

Copies of this patent may be obtained for five cents each, by addressing the "Commissioner of Patents, Washington, D. C."

I claim:

1. A surfacing roll comprising a hollow cylinder having end walls formed integral with the circumferential walls, one of said end walls being provided with bearings adapted to receive the ends of a pair of clamping members and the opposite end wall being provided with an opening through which said clamping members may be inserted into said cylinder, and a block removably closing said opening and provided with 40 bearings adapted to receive the opposite ends of said members, said members being removable from the cylinder through said opening upon removal of said block.

2. A surfacing roll comprising permanently connected end and side walls, a clamping device disposed within and extending longitudinally of said cylinder, one of said end walls being provided with an opening through which said clamping device may be 45 introduced into and withdrawn from said cylinder, and a removable member normally closing said opening, said member and the opposite end wall of the cylinder being constructed to normally support said clamping device in operative position.

ARTHUR E. CHAPPELL.
